UNITED STATES PATENT OFFICE

WILLIAM J. MCKEE, OF LOS ANGELES, CALIFORNIA

CLAMP

Application filed February 18, 1928, Serial No. 255,303. Renewed November 13, 1930.

This invention relates to the class of molds and pertains particularly to a mold form clamp.

The primary object of this invention is to provide in a manner as hereinafter set forth, a mold clamp for use in the construction of poured concrete hollow building walls which will permit the quick and easy placement and removal of forms.

10 Another object of the invention is to provide, in a manner as hereinafter set forth, a mold form clamp which will hold the forms in such positions that after the plastic material has set the form boards can be released and removed without wrenching or prying the same thereby eliminating the danger of cracking the green concrete.

Another object of this invention is to provide, in a manner as hereinafter set forth, 20 a mold form clamp for use in constructing hollow building walls which will maintain inner form members in set position in such a manner as to permit the forming of the wall sections in spaced relation without concrete connecting bodies, thereby providing 25 a hollow wall without means between the sections whereby moisture can pass from the outer wall section to the inner section.

A still further object of the invention is to 30 provide a mold clamp for use in constructing hollow building walls which will maintain the mold boards in such a position as to permit the insertion in the wall of vertical, horizontal and cross tie reinforcing bars.

35 Numerous other objects and advantages of the present invention will become apparent as the description of the same proceeds and the invention will be best understood from a consideration of the following detailed description taken in connection with the accompanying drawings, forming a part of this specification, with the understanding, however, that the invention is not confined to any strict conformity with the showing of the drawings, but may be changed or modified so long as such changes or modifications mark no material departure from the salient features of the invention as expressed in the appended claims.

50 In the drawings:—

Figure 1 shows a side elevation of the clamp structure embodying the present invention.

Figure 2 is a top plan view of the structure shown in Figure 1.

Figure 3 is a sectional view taken upon the line 3—3 of Figure 1.

Figure 4 is a view in side elevation of the clamp structure.

Figure 5 is a section through the lower 60 portion of a wall showing the manner in which the clamp maintains the form boards in position.

Figure 6 is an outside elevational view of 65 wall forms in position at the corner of a building wall showing the clamps embodying the present invention, holding the form boards in position.

Figure 7 is a plan view of the wall corner structure shown in Figure 6.

Figure 8 is a detailed view of a hinged member employed to maintain the inner form bodies in proper spaced relation.

Figure 9 is a detailed perspective view of 75 one corner of a wall constructed with the use of the present clamp devices, showing the manner in which the reinforcing elements can be placed in position.

Figure 10 is a sectional view through a 80 wall and window casing positioned therein showing the manner in which the wall can be formed directly about the window frame, and

Figure 11 is a horizontal sectional view 85 through one side of a window frame installation such as that shown in Figure 10, looking downwardly and showing the manner in which the concrete can be poured to position about the window frame.

Referring now to the drawings in detail, wherein like numerals of reference indicate corresponding parts throughout the several views, the mold board clamp structure with the inner mold plate attached thereto is indicated generally by the numeral 1 and as is shown this clamp, of which a plurality is used in maintaining the form boards for a wall in position, comprises a pair of substantially L-shaped members 2 100

each member having a long leg 3 and a right angularly related short leg 4.

Each of the long legs of the clamp member is enlarged adjacent each end as at 5 and has a passage 6 formed through each of the enlarged portions which passages, when the short legs 4 of the members 2 are secured together as shown and as herein-after described, are parallel and open at 10 one end toward the center of the clamp, as shown. In each of the passages or recesses 6 there is eccentrically mounted a binding member in the form of a disk 7 each of which members 7 carries an arm 8 which 15 extends from the passage 6 beyond the outer side or edge of the clamp leg member 3. As is clearly shown in Figure 1 a portion of the periphery of each disk 7 extends beyond the inner edge of its supporting leg 3 and when the disk is rotated the periphery thereof will be still further projected inwardly toward the center of the clamp.

Each of the short legs 4 of each clamp member 3 has a pair of triangularly formed bodies upon the inner edge thereof as indicated at 9, the basal portion of that triangular body which is adjacent the outer end of each short leg being in alignment with the adjacent end of the leg whereas the basal portion of the inner triangular body is in opposition to the inner edge of the adjacent long leg 3 and is spaced a predetermined distance therefrom. Between the triangular portions 9 of each short leg, 30 the inner edge of the leg is provided with a series of notches 10.

The short legs 4 of each of the clamp members 2 are positioned in side by side relation as shown in Figure 1, the free end of each 40 short leg being spaced from the long leg 3 of the adjacent member, a distance equal to the space between the inner triangular member 9 and the adjacent integral long leg member 3. Suitable bolts 11 are employed 45 to secure the short legs of the member in the relation described.

Each of the short legs 4 of each clamp structure is provided adjacent its inner edge and adjacent its point of joinder with a long 50 leg 3, with a longitudinally extending slot 12 through which a supporting bolt 13 passes, which bolt is carried by a head member 14. The head member 14 supports a relatively long narrow metal wear or friction strip 15 against which the adjacent eccentrically mounted disks 7 bear when rotated to operative position.

When the form board clamps are to be put into use, the outer boards 16 of the 30 form are first placed in position on the previously cast foundation, and the required number of clamps 1 are then arranged in place to straddle the form boards in the manner shown in Figure 5, the upper edges 35 of the form boards 16 being positioned be-

tween the inner faces of the friction strip 15 and the basal portion of the angular bodies 9 carried by the short legs 4 of the clamp members.

The inner plates of the wall form which 70 coact with the outer form boards 16 to form the inner and outer wall sections 17 and 18 form a part of the clamp structure and these inner form plates are indicated by the numerals 19 and 20. The plates 19 75 and 20 are preferably formed of sheet iron and are placed in the proper spaced parallel relation between and spaced from the inner faces of the outer form members 16 as shown in Figure 5, the top edges of the plates 80 engaging in certain of the notches 10 by which they are held at their upper edges in proper spaced relation.

In order to maintain the lower portions 85 of the plates 19 and 20 in the proper spaced relation, one of the plates, for example, plate 20, is provided with an especially designed spacing brace member indicated as a whole by the numeral 21. This brace and spacer is in the form of a hinge, having 90 one leaf 22 secured to the inner face of the plate 20 while the other leaf 23 is adapted to be positioned substantially horizontally between the plates 19 and 20, the leaf 23 95 having the brace arm 24 formed integral therewith and extending from one face thereof for engagement with previously formed wall structure to prevent the leaf from swinging below the horizontal. The free end of the leaf 23 is turned to provide a foot 100 25 which bears against the inner face of the adjacent form plate 19 in the manner shown in Figures 1 and 5. When the clamps have thus been placed in position over the outer form boards 16 the inner plates 19 and 20 are placed in the position 105 described, the lower ones of the eccentrically mounted disks 7 are rotated by forcing the arm 8 downwardly to force the lower edges of the form boards 16 inwardly against the adjacent face of the previously cast foundation wall, the forcing of the brace member 21 into its position securely clamping the plates 19 and 20 against the inner faces of the previously formed foundation wall sections. After this the upper ones of the 115 eccentric disks 7 are rotated by forcing the arms 8 downwardly to press the upper edges of the mold boards 16 against the triangular bodies 9, this inward movement of the board and the friction strips 15 being permitted by the mounting of the supporting bolts 14 120 and the friction strips 15 in the slot 12.

It is, of course, to be understood that previous to placing the mold boards 16 in the 125 positions described, and the actuating of the eccentricities 7, the foundation must be first provided with low inner and outer wall sections corresponding to those indicated by the numerals 17 and 18, this being done by 130

the constructing of the usual forms and casting of these low walls in the usual manner.

From the foregoing description, it will be readily seen that by the use of outer mold boards held in position by clamp members of the character herein described in association with inner form plates maintained in position by the clamp members, use of vertical reinforcing bars 26 and horizontal and transverse bars 27 and 28 respectively may be made without difficulty in placing them in position. It will be seen that the horizontal bars can be easily laid in position on the previously formed wall structure and after the form clamps have been removed slots will have been formed by the legs 4 of the clamps transversely of the wall sections in which the reinforcing connecting bars 28 between the wall sections 17 and 18 may be placed.

In the constructing of walls of the hollow type, by the use of form clamps of the character described, the inner and outer wall sections may be maintained in spaced relation with nothing connecting therebetween through which moisture can pass from the outer to the inner wall sections, the connecting bars 28 not acting as moisture absorbers. To prevent rusting of the connecting bars 28 the same may be coated with asphalt or a similar preparation.

When finishing off the top of the wall of the character herein described, the outer mold board 16 can be retained in position right to the top of the wall, whereas the inner plates 19 and 20 can be eliminated so as to permit the forming of a solid beam such as that indicated at 29 in Figure 10, to connect the top edges of the outer and inner wall sections 17 and 18.

By the use of forms held in position with clamps of the character described, windows or doors of any size may be placed in any wall without having to cut or fit forms either inside or outside, as the outside wood forms are placed all around the building and window and door jambs are set therebetween with the jambs furred out to the full width of the wall. As the inside form plates 19 and 20 are of thin sheet metal they are simply slipped into position with their edges abutting the window or door jamb. Thus after the concrete has been poured and has set and forms removed, it will be found that the concrete has formed itself tightly about the window or door frames thus making a perfect air tight fit or joint therebetween.

The manner in which the concrete after setting snugly engages throughout the sides of the window frame, is clearly shown in Figures 10 and 11, the window frame here being indicated generally by the numeral 30. It will be readily understood from the disclosure that little difficulty will be en-

countered in setting window and door frames in a wall and thus time and labor will be saved.

From the foregoing description it will be readily seen that the herein-described clamp can be easily and quickly placed in or removed from position, will efficiently maintain form boards in their positions until the cement has set, and can be readily released by shifting the eccentric disks 7 to permit the removal of the form boards without danger of cracking or breaking the wall.

What I claim is:

1. A form clamp for hollow poured concrete walls employing the usual form boards for the outer faces of the wall, comprising a pair of elongated members designed to extend substantially vertically over the outer mold boards, means for connecting said members at their upper ends, a pair of mold plates designed to be arranged in spaced relation to form the hollow center of the wall, means for adjustably connecting the top edges of said mold plates with said connecting means, a brace element carried by one of said plates designed to engage the adjacent plate to maintain the lower edges of the plates in spaced relation, a swinging guard strip carried by said connecting means and designed to be arranged between an elongated member and the adjacent outer mold board, means carried by said elongated members for exerting an inward pressure against the guard strips and the adjacent outer mold boards, and means associated with said connecting means for limiting the inward movement of the outer mold boards under the pressure exerted thereon by the said pressure exerting means.

2. A wall mold board clamp of the character described comprising a pair of substantially L-shaped members having a long arm and a short arm, means for securing the short arm of the members in oppositely directed side by side relation to arrange the long arms of the members in spaced parallel relation, eccentrically pivoted clamp members carried by the long arms of the members for engagement with mold boards arranged therebetween substantially as described, and guard strips suspended from said short legs for interposition between the clamp members and the mold boards.

3. A wall mold board clamp of the character described, comprising a pair of substantially L-shaped members having a long arm and a short arm, means for securing the short arm of the members in oppositely directed side by side relation to arrange the long arms of the members in spaced parallel relation, eccentrically pivoted clamp members carried by the long arms of the members for engagement with mold boards arranged therebetween, guard strips suspended from said short legs for interposition be-

tween the clamp members and the mold boards, means forming a part of the structure of said short legs for limiting the inward movements of the mold boards under the pressure of the clamps, and means for connecting a pair of mold plates with said short legs of the members to maintain the plates in spaced relation with respect to one another for the purpose described.

4. A wall mold board clamp comprising a pair of substantially L-shaped members having a long arm and a short arm, means for securing the short arms of the members in oppositely directed side by side relation to arrange the long arms of the members in spaced parallel relation, guard strips suspended from said short legs for engaging the mold boards, means carried by the long arms for urging the guard strips toward the mold boards, and depending abutment bodies carried by the short arms in spaced relation to the long arms of the members for engaging the inner faces of the mold boards.

5. A wall mold board clamp comprising a pair of substantially L-shaped members having a long arm and a short arm, means for securing the short arms of the members in oppositely directed side by side relation to arrange the long arms of the members in spaced parallel relation, guard strips pivotally suspended from said short arms for engaging the mold boards, and eccentrically mounted pivoted clamp members carried by the opposite ends of the long arms of the members for engaging the guard strips adjacent to the opposite ends thereof.

In testimony whereof I affix my signature.
WILLIAM J. McKEE.
